UNITED STATES PATENT OFFICE

2,426,078

WASHING MACHINE TRANSMISSION

Rex Earl Bassett, Jr., Miami Beach, Fla., assignor, by mesne assignments, to American Machine and Metals, Inc., East Moline, Ill., a corporation of Delaware

Original application January 27, 1939, Serial No. 253,038. Divided and this application June 23, 1944, Serial No. 541,776

2 Claims. (Cl. 74—368)

1

This invention relates to washing machines and particularly transmission mechanism for automatic washing machines.

This application is a division of my co-pending application Serial No. 253,038 filed January 27, 1939.

An object of the invention is to simplify the transmission mechanism, and to provide a transmission mechanism of the type which is particularly adapted to be located on the end wall of the tub, where it is directly connected selectively at different speeds to the rotor of the machine.

The above and other objects and features of the invention, including various novel combinations and desirable particular constructions, will be apparent from the following description of the illustrative embodiment shown in the accompanying drawings, in which:

Figure 1 is a vertical section through the washing machine;

Figure 2 is a partial horizontal section through the washing machine on the line 2—2 of Figure 1; Figure 3 is a wiring diagram; and

Figure 4 is a cycle diagram.

The washing machine of Figure 1, except as hereinafter described in connection with Figure 2, may be substantially of the construction and have substantially the method of operation described in United States Patent No. 2,165,884, issued July 11, 1939, to me jointly with John W. Chamberlin, with the modifications described in United States Patent No. 2,173,603, issued September 19, 1939, to Adiel Y. Dodge.

The washing machine illustrated in Figure 1 includes a cylindrical tub 10 arranged with its axis horizontal, and having an opening in its front side provided with a door 12 for the introduction of the clothes to be washed. The tub 10 contains a perforated drum or cylindrical clothes container or rotor 14, formed with suitable ribs or baffles and having an opening registering with the door 12, and which is carried by a short drive shaft 16 extending outwardly from its end and journaled in bearings carried in a transmission housing 17 which in turn is carried by diverging stampings or similar spaced members 18 and 20 forming the rear wall of the tub 10. The entrance of the shaft 16 to the transmission housing 17 is preferably sealed against the passage of oil and water by a suitable seal 19 (Fig. 2).

The tub 10 is mounted on supports such as saddles 22 resting on a base 24, and is preferably secured to the saddles by steel straps 23 fastened at opposite sides of the saddles and passing over

2

the tub. The machine may be enclosed in a cabinet 26, formed of suitable steel panels.

Hot and cold water are supplied to the machine through conduits 28, one behind the other in Figure 1, controlled by valves 30, one behind the other in Figure 1, actuated by solenoids 32, one behind the other in Figure 1, the mixed water from the two inlet valves 30 being carried by a conduit 36 to an inlet nozzle 38 at the edge of the door 12. The cold water line solenoid 34 preferably has arranged in series therewith a thermostatic switch 40, so that when water at a predetermined temperature is desired, sufficient cold water is injected to lower the inlet water temperature.

If desired, a manually operable switch 42 may be provided to connect when desired, as for example when washing woolens, the cold water solenoid circuit with the hot water circuit so that the cold water circuit will always be closed through the thermostatic switch 40 whenever the hot water is turned on, thereby limiting the maximum temperature of the water in the machine. The machine is provided with a door 44 for introducing soap powder or the like, to form suds.

The tub 10 is provided with a sump or drain 46 connected, through a drain valve controlled by a solenoid 48, to a drain pump 50, the outlet of which is connected to a drain conduit 52. The tub 10 also communicates with the bottom of a float chamber 54 containing a suitable float 55 having a connecting rod 56 provided with stops operating a float switch 58.

The transmission contained in the housing 17 is provided with a pulley 60 driven by a belt 62 from a pulley 66 on the armature shaft of an electric motor 68. The armature shaft of the motor 68 preferably projects from the opposite end of the motor and is connected at that end to drive the pump 50, which may be mounted directly on the motor. The motor and pump may be provided with lateral arms 70 pivoted on a fixed shaft 72 carried by the saddles 22, so that the weight of the motor tensions the belt 62.

Referring now to Figure 2, the transmission casing 17 is preferably provided on its front face with a pad 74 annularly surrounding the shaft 16 and adapted to have the stamping 18 secured thereto by suitable fastenings such as screws or the like. Adjacent the rear face of the transmission casing 17 is provided an annular flange 76 which is adapted to have secured thereto in a similar manner the stamping 20. The rear face of the transmission housing 17 is closed by a removable cover plate 78. The two conical stamp-

ings 18 and 20 converge into annular contact at their peripheries and are joined to the tub by a V-section clamping ring 77 adapted to draw the stampings into close contact with a radial flange 78 formed on the tub. A suitable rubber gasket (not shown) may be used to form a watertight joint here.

The shaft 16 is journaled in the transmission housing 17 by means of a pair of ball bearings 80 and 82 seated in coaxially arranged bosses formed in the transmission housing cover and the housing proper respectively.

The pulley 60 is formed integrally with a sleeve 84 projecting into the transmission housing 17 in spaced parallel relation to the shaft 16 and rotatably mounted in the transmission housing cover on a ball bearing 86. Within the transmission housing this sleeve is provided with gear teeth forming a drive pinion 88. The drive pinion 88 meshes with a large gear 90 coaxially mounted on the shaft 16 and adapted to drive said shaft through a one-way clutch 92 of any suitable type, but here shown as the well-known cam and roller type. The gears 88 and 90 form a low speed drive for the shaft 16 and drum 14.

Coaxially mounted within the sleeve 84 is a shaft 94 having one end projecting from said sleeve within the transmission housing 17 and journaled in a boss 96 formed in said transmission housing, and having its other end projecting externally of the transmission housing 17 through a suitable oil seal 98. On this other end of the shaft 94 is secured a clutch plate 100 having a suitable friction face 102 adapted to engage a clutch surface 104 formed on the pulley 60. The clearance between the clutch facing 102 and clutch surface 104 may be adjusted by means of a pair of lock nuts 108 threaded on a reduced portion 108 of the shaft 94.

A high speed pinion 110 is keyed to the shaft 94 within the transmission housing 17 intermediate the end of the sleeve 84 and the boss 96. The high speed pinion 110 is in mesh with a high speed gear 112 keyed to the shaft 16, and these gears 110 and 112 form a high speed drive for the shaft 16 when the clutch 100-104 is engaged. When the shaft 16 is operated at high speed it over-runs the low speed gear 90 by means of the one-way clutch 92.

The clutch 100-104 is arranged to be engaged by an axial thrust to the right exerted on the shaft 94 by a thrust bearing 114 which is engaged by a roller 116 on one arm of a bell crank lever 118. The bell crank lever 118 is pivoted on a bracket 120 secured to the wall of the transmission casing 17 and its other arm extends outside of the transmission casing 17 through a slot 120 which may be sealed by a rubber cup 122. A solenoid 124 secured to the flange 78 is provided with a plunger 126 secured by means of a spring 128 to the said other arm of the bell crank lever 118, and the solenoid is adapted, when energized, to swing the bell crank-lever 118 in a clockwise direction and thus engage the clutch 100-104.

It will be seen that, by my novel construction, I have incorporated the transmission housing 17 into the framework of the washing machine as an integral part thereof, and that I have made the drum shaft 16 an integral part of the transmission, thus materially simplifying the construction and reducing the cost of the machine.

The motor connections and the solenoids 32, 34, 48 and 124 are controlled by a motor driven

automatic cyclic switch 130. The switch 130 may be of the type fully described in my Patent No. 2,176,195, dated October 17, 1939, and includes a small constant speed clock motor 132 operating,

5 through reduction gearing 134 and a one-way drive device 136, a shaft 138. The shaft 138 carries an indicator 140 which travels over a suitable dial on the front panel of the machine and which can be operated manually, as permitted 10 by the one-way drive device 136, to advance the shaft 138 to shorten one or more of the steps of the washing and drying cycle.

The shaft 140 carries a series of control cams 142, 144, 146, 148 and 150. The cams operate as 15 described in my aforementioned Patent No. 2,176,195 to open and close contacts 152 to control circuits through the motors 88 and 132 jointly, and the solenoids 32, 34, 48 and 124 respectively between a conductor bar 154 connected to one line 20 156 of a source of supply of electric current, to the opposite line 158 of the current supply.

It will be noted that the circuits through the solenoids 32 and 34 are connected to the line 158 through the float switch 58. Also connected 25 through the float switch is the circuit through the clutch operating solenoid 124, thus making it impossible for the drum 14 to be operated at high speed unless the water has been drained out of the machine and the float switch 58 closed. The 30 motor circuits and the drain solenoid circuit are connected directly to the line 158.

In operation of the machine, the indicator member 140 is turned slightly by the operator, 35 after the machine has been filled with clothes to be washed and the door 12 has been closed, to actuate the cam 142 to close a circuit from the line 156 through the conductor bar 154, contacts 152 and the switch motor 132. Thereupon the 40 switch motor 132 drives the shaft 138 at a constant speed to cause the machine to carry out the cycle of washing and rinsing and drying for which the cams 142-150 are designed. This may be the cycle shown in Figure 4 (read clockwise), or any 45 desired modification of that cycle, the exact sequence and duration of the various steps of the cycle being determined by the shapes of the various cams.

In the cycle diagram of Figure 4 the cross-hatched segments indicate periods in which the 50 respective motors and solenoids are energized, and it is believed that it will be readily understood how the machine, with my novel arrangements and constructions, carries out successfully the 55 operations of (1) filling the tub with a predetermined quantity of warm water, soaking the clothes while tumbling them in the tub and then draining the water from the tub; (2) stopping the machine so that soap may be added and the 60 machine manually restarted; (3) filling the tub again and tumbling the clothes at low speed for a period of time determined by the manual advancing of the shaft 138 by the indicator knob 140; (4) draining out the wash water and spraying 65 rinse water over the clothes to flush out scum; (5) tumbling the clothes without water in the tub to distribute them evenly around the periphery of the drum; (6) partially extracting the water from the clothes by operating the drum at high speed; (7) filling the tub with clean water and tumbling the clothes at low speed for rinsing; (8) a second drain and flush; (9) a second distribution; and (10) a complete extraction after 70 which the machine stops with the clothes in condition for final drying by evaporation and ironing.

While only one embodiment of my invention has been described in detail, it is not my intention to limit the scope of the invention to that particular arrangement or otherwise than by the terms of the appended claims.

I claim:

1. A transmission comprising a main shaft, a rigid metal housing for the transmission having bearings in which said shaft is mounted, a second shaft extending across said housing parallel to the first said shaft and having spaced bearings in said housing, drive means on said second shaft outside said housing, gears within said housing for driving the first shaft from the second shaft, two conical support members surrounding said housing, the said rigid housing being firmly attached at its ends to each of said conical members and serving rigidly to connect them together interiorly of their peripheries, whereby the said conical members and their support form sturdy torque resisting members for withstanding the torque reaction of said second shaft, gears and first shaft.

2. A transmission substantially as described, comprising a housing, a shaft having an end portion extending from said housing, spaced bearings in said housing supporting said shaft inside said housing, gearing inside said housing for driving said shaft, a drive pulley outside said housing, a

member rotatable with said pulley and extending into said housing and driving said gearing thereby to drive said shaft at a relative speed determined by said gearing, a clutch member also outside said housing and adjacent said pulley, a driving connection from said clutch member to said shaft, operating means for said clutch member whereby said clutch member is operable to cause said pulley to drive said shaft through said driving connection at a relative speed higher than that first mentioned.
